United States Patent Office.

G. W. BALL, OF CINCINNATI, OHIO.

Design No. 2,695, dated July 9, 1867.

DESIGN FOR A COOK'S STOVE.

The Schedule referred to in these Letters Patent and making part of the same.

TO WHOM IT MAY CONCERN:

Be it known that I, G. W. BALL, of Cincinnati, Hamilton county, Ohio, have invented a new design for a Cooking-Stove; which design is represented in the accompanying illustration, which forms part of this specification.

I claim as my invention, and desire to secure by Letters Patent—

The design for a cooking-stove, substantially as represented in the accompanying illustration.

In testimony of which invention I hereunto set my hand.

Witnesses:

GEO. H. KNIGHT,
JAMES H. LAYMAN.
